AUDIO FREQUENCY AMPLIFIER

Winfield R. Koch, Merchantville, N. J., assignor
to Radio Corporation of America, a corpora-
tion of Delaware

Application November 30, 1936, Serial No. 113,473

4 Claims. (Cl. 179—171)

The present invention relates to audio frequency amplifiers, and more particularly to audio frequency amplifiers in connection with radio receiving apparatus and the like having a common power supply connection with the receiver, whereby the amplifier and the receiver are jointly subject to potential variations from the source.

It is an object of the present invention to provide an improved filter connection in an audio frequency amplifier whereby the effect of anode potential variations tending to cause flutter or pulsations is neutralized.

The invention is particularly adapted to the power amplifier stage of a radio receiver or the like whereby the amplifier stage may be operated from a single power supply device without undue interference or flutter in the receiver circuit.

It has been found that the tendency of a radio receiver to flutter may be minimized considerably if the grid filter capacitor in the audio amplifier output stage which creates an interfering surge in response to strong signals, is returned to the plate supply positive lead rather than to ground or chassis.

The grid filter, with the filter capacitor returned to ground, has normally a time constant much slower than the time constant of the power supply means, consequently the grid bias voltage tends to remain constant during a surge. If the grid filter capacitor is connected to a point at which the surge originates, a counter-voltage is impressed upon the grid minimizing the surge and its effects.

The tubes in the amplifier may be considered to act as a low impedance alternating current path, while at the same time offering a high resistance to direct current.

The invention will, however, be better understood from the following description when considered in connection with the accompanying drawing and its scope will be pointed out in the appended claims.

In the drawing, Fig. 1 is a schematic circuit diagram of an amplifier embodying the invention and

Fig. 2 is a further schematic circuit diagram of an output amplifier for a radio receiver showing a modification of the invention.

Referring to Fig. 1, an amplifier tube 5 is provided with an input circuit 6 for receiving audio frequency signals, and an anode output circuit 7 connected through an anode output resistor 8, and a coupling capacitor 9, with an audio frequency output circuit 10.

Anode current for the amplifier 5, is provided

between a positive supply lead 11 and a negative ground lead 12. In the positive supply lead 11, between the output resistor 8 and said lead, a series filter resistor 13 is connected in circuit and is provided with a by-pass filter circuit 14, 15 to ground.

The filter circuit comprises a second amplifier tube 15 having a control grid 16, an anode 17, and a cathode 18. The latter is connected to the ground lead 12, through a self bias resistor 19, and grid potential is applied therefrom to the control grid 16, through a grid resistor 20 connected between the grid and ground.

Potential surges in the supply circuit, causing a variation in the potential between leads 11 and 12, and surges caused by strong signals applied to the grid circuit 6, tending to make the anode current vary rapidly at audio and sub-audio frequencies are applied to the control grid of the regulating tube 15 through a coupling capacitor 21, connected between the junction of the output impedance or resistor 8 and the filter resistor 13 at the terminal 22.

The instantaneous surges are conveyed through the coupling capacitor 21 and cause the plate current of the regulating tube 15 to vary, thereby tending to maintain the potential at the point 22 constant and opposing the change which is occurring at that instant.

The reactance of the coupling capacitor 21 between the control grid 16 of the regulating tube and the anode 17 should be relatively low, while the grid impedance to ground provided by the resistor 20 should be relatively high.

The variation in potential which may occur at the terminal 22 may be represented by an alternating voltage E which is applied to the plate 17 and to the grid 16 through the capacitor 21. In the plate circuit of the tube the amplified grid voltage μE , is effectively in series with the applied voltage, the alternating component of the plate current will, therefore, be

$$I = \frac{E + \mu E}{R_p} = \frac{(1 + \mu)E}{R_p}$$

and the impedance, in effect, will be

$$R = \frac{E}{I} = \frac{R_p}{\mu + 1}$$

For amplification factors of medium or high values, this R is approximately the reciprocal of the mutual conductance of the tube.

The tube circuit 14 therefore takes the place of a by-pass capacitor and operates to amplify the effect of the capacitor 21. At a flutter fre-

quency of two cycles per second, for example, this circuit will offer an impedance of substantially 1,000 ohms, or the equivalent of 80 microfarads capacity between the terminal 22 and ground. This is for the reason that the tube is connected in a circuit to act as a low impedance alternating current path, while at the same time offering a high resistance to direct current. The triode shown may have direct current anode circuit resistance of substantially three times the normal resistance to alternating current, depending upon the bias on the grid. With the same tube connected as shown in Fig. 1, the plate circuit impedance to alternating current will be only one-fiftieth as much as the resistance to direct current. Because of the low impedance between point 22 and ground, variations in the voltage of the anode of tube 5 will cause the voltage to appear chiefly across resistor 8, and only a small voltage will occur between point 22 and ground. Thus variations in plate current of tube 5 will cause only small variations in current through resistor 13, and the potential of the supply voltage lead 11 will be little affected. Likewise, any variations in the voltage supply potential, caused by other amplifier tubes, would be made to drop most of the voltage in resistor 13, and only a small part of such variation in supply voltage would reach the anode 7 and succeeding parts of the amplifier through condenser 9 and lead 10.

Referring now to Fig. 2, a pair of balanced or push-pull connected audio frequency amplifier tubes 25 and 26 are connected between a push-pull or balanced input transformer 27 and a push-pull or balanced output transformer 28, to supply audio frequency power to a loudspeaker 29 when audio frequency signals are applied to the input winding 38 of the input transformer 27. The cathode heating supply circuit for the amplifier, indicated at 31, is in common with a radio receiver 32, which may supply signals to the input terminals 38, and is connected to ground, as indicated at 33, within a power supply device indicated at 34, which receives power from alternating current supply leads 35-35.

The power supply unit 34 includes a rectifier indicated at 36 to provide rectified and filtered direct current potential at suitable anode potential between output leads 37 and 38, the final filtering being provided by a shunt by-pass filter capacitor 39.

The negative potential supply lead 38 from the rectifier is connected to ground or chassis 39 through the loudspeaker field indicated at 40, which provides a filter choke coil in the negative lead and a source of grid bias potential for the tubes 25 and 26. A connection lead between the negative terminal of the potential source 40 and a center tap 42 on the input transformer is provided with a series filter resistor 43 for the biasing potential for the tubes 25 and 26. A plate potential supply lead 44 is connected between a center tap 45 on the primary of the output transformer and the positive supply anode lead 37. A filter capacitor 46 is also provided between the terminal 45 and the ground.

The radio receiver is also connected in common with the amplifier, to the anode potential supply leads 37 and 38, as indicated at 47 and a suitable filter capacitor is provided therefor as indicated at 48.

Variations in anode potential caused by heavy load placed upon the output amplifier and audio or sub audio potential variations resulting therefrom may be transmitted to the radio receiver

and may adversely affect the operation of the tube circuits therein, as is well known. To prevent this effect, the grid filter, including the series resistor 43, is completed by a filter capacitor 49 connected between the grid terminal 42 on the transformer 27 and the positive supply lead 37 through a lead indicated at 50. With this connection, a signal surge tending to cause an increase in anode current through the tubes 25 and 26, and a corresponding reduction in voltage on the positive lead 37, is conveyed through the filter or controlling capacitor 49 directly to the grids of the amplifier tubes, causing said grids to become more negative and this, in turn, tends to counteract the tendency of the anode current to increase, destroys the effect of the surge on the supply circuit, and prevents the same from being transmitted to the radio receiver circuits.

It will be appreciated that if the usual grid filter is provided for the purpose of reducing the effect of ripple resulting from alternating current rectification, the time constant of the circuit so formed is relatively slow and tends to maintain the grid bias potential constant during the surge, thereby permitting the anode current to rise.

However, with the connections shown, the amplifier tubes are utilized to absorb the alternating current or surge voltage. The circuit feeds back only the undesired effects of the signal or surge and not the surge itself, since the degenerative feedback connection is provided through a reactance device of low impedance to alternating current, while preventing the flow of direct current because of the high direct current resistance.

In an amplifier as shown, using RCA 2A3 tubes and a potential of 300 volts between the leads 37 and 38, a surge conducting capacitor 49 of .25 microfarad is provided in connection with a filter resistor 43 of substantially 56,000 ohms. As in the preceding example, the capacitor 49 should have a relatively low reactance, while the grid filter resistor 43 should have a relatively high resistance. For example, in the circuit of Fig. 1 the capacitor 21 may have a value of 1.0 microfarad and the resistor 20 may have a resistance of substantially 1 megohm, the requirements depending upon circuit and the tubes used.

It has been found preferable, in commercial radio receivers for high fidelity output, to separate the balanced grid circuit from the filter network by introducing a resistor 43a between the mid-terminal of the input transformer and the mid-tap on the filter, between the resistor and the capacitor. This may have a resistance of 100,000 ohms with 2A3 output tubes as shown and is preferably higher in resistance than the resistor 43.

I claim as my invention:

1. In an audio frequency amplifier, a filter circuit comprising a filter resistor and an electric discharge amplifier tube, means providing a relatively high impedance path between the input electrode thereof and the cathode, and a capacitor providing a relatively low reactance path between the anode and said input electrode and providing the sole impedance element in circuit between said electrodes, said anode being connected to a point in said amplifier at which surges tend to develop.

2. In an audio frequency amplifier of the push-pull type having a balanced input circuit provided with a connection for grid bias potential

supply, means providing a balanced output anode circuit for said amplifier having a center-tap connection, means for applying audio frequency and sub-audio frequency voltages to the 5 control electrodes of the push-pull amplifier simultaneously in parallel, said means comprising a capacitor of low reactance at said frequencies connected as the sole impedance element between the anode circuit center-tap connection and said bias potential supply connection, and means for supplying a biasing potential to 10 said first-named connection comprising a filter resistor having a relatively high resistance with respect to the reactance of said capacitor.

15 3. In an audio frequency amplifier of the balanced type including a pair of electric discharge amplifier tubes in push-pull relation to each other, the combination of anode potential supply means for said tubes comprising a positive supply lead 20 and a negative supply lead, means providing a balanced input circuit for said amplifier having a bias potential supply connection, means providing a balanced output anode circuit for said amplifier having a center-tap connection with 25 said positive supply lead, a capacitor having a relatively low reactance to audio frequency currents and sub-audio frequency currents connected as the only impedance element in circuit

between the said center-tap connection and said bias potential supply connection, a filter resistor connected between said capacitor and a point of negative biasing potential supply in said negative supply lead, and means for isolating said center-tap connection from said last-named point of connection between said resistor and capacitor comprising a series resistor having a resistance at least as great as said first-named resistor.

4. In an audio frequency amplifier of the balanced type, comprising a pair of electric discharge amplifier devices connected in balanced relation to each other, the combination of an input transformer for said amplifier having a secondary winding provided with a bias potential supply connection, an output transformer having a primary winding provided with a center-tap, a capacitor providing the only impedance in circuit between said bias potential supply connection and said center-tap and providing a path of low reactance for audio frequency currents therebetween, means providing a source of biasing potential for said amplifier devices, and a resistor connected between the center-tap of the input transformer secondary and said source, said resistor having a relatively high resistance with respect to the reactance of said capacitor.

WINFIELD R. KOCH.
